(57) **CLAIM**

The ornamental design for a foot for ladder as shown and described.

DESCRIPTION

FIG. 1 is an upper perspective view of a foot for ladders;

FIG. 2 is a lower perspective view thereof;

FIG. 3 is a bottom view thereof;

FIG. 4 is a top view thereof;

FIG. 5 is a front view thereof;

FIG. 6 is a rear view thereof; and,

FIG. 7 is a left-side view thereof.

The broken lines shown in the figures represent portions of
a foot for ladder that form no part of the claimed design.
